UNITED STATES PATENT OFFICE.

WILLIAM H. RAPP, OF PHILADELPHIA, PENNSYLVANIA.

HEADLIGHT.

Application filed February 21, 1923. Serial No. 620,463.

To all whom it may concern:

Be it known that I, WILLIAM H. RAPP, a citizen of the United States, and a resident of Philadelphia, Pennsylvania, have invented 5 certain new and useful Improvements in Headlights for Automobiles and the like, of which the following is a specification.

My invention relates to that type of headlight in which the lamp forming the source 10 of illumination is at all times concealed from view, thereby eliminating the blinding effect incident to exposure of a brilliant lighting medium within the range of vision of persons approaching the headlight.

The main object of my invention is to provide a cheap and efficient means for carrying and shielding the source of illumination and of a character which may be fitted to any ordinary headlight or automobile 20 lamp structure now in use; such means serving to support an electric bulb forming the source of illumination and to conceal the same from the front of the headlight or lamp structure.

A further object of my invention is to provide a light supporting structure that will provide a suitable source of illumination and by means of which the rays of light emanating from the electric lamp will 30 be projected forward at a slightly downward inclination and serve to light the road in front of the automobile instead of being diffused in all directions.

A further object of my invention is to provide a combined shield and electric lamp-carrying element of a single integral member and of simple construction, attachable to any of the common or standard forms of headlight structures.

These and other features of my invention are more fully described hereinafter, reference being had to the accompanying drawings, in which:

Figure 1 is a sectional elevation of an ordinary automobile lamp of the headlight type to which my improved shield and lamp-carrying attachment may be applied, taken on the line I—I, Fig. 2.

Fig. 2 is a sectional elevation on the line 45 II—II, Fig. 1, showing a rear elevation of my improved shield and lamp carrying attachment.

Fig. 3 is a detached perspective view of my improved shield and electric lamp support forming the subject of my invention.

Figs. 4 and 5 are enlarged sectional views

illustrating modified constructions within the scope of my invention.

Fig. 6 is a sectional view on the line VI—VI, Fig. 5.

Fig. 7 is a plan view, on a reduced scale, of a blank from which the form of shield and lamp-carrying structure shown in Figs. 1, 2, 3 and 4 may be made, and

Fig. 8 is a similar plan view of a blank 65 from which the form of shield and lamp-carrying structure shown in Fig. 5 may be made.

In the drawings, 1 represents a lamp casing, which may be of ordinary parabolic 70 form in cross-sectional contour, or semi-circular in shape, within which is located a reflector 2, which may be of any usual type, semi-circular, parabolic or the like, as employed in any ordinary headlight structure. 75 At the front of the structure is the usual door frame 3, carrying a glass 4, and this glass may be of the usual character, or of any of the lens types commonly employed. The door may be of the hinged or rotatable 80 type, which may be opened, in order that repairs to the structure may be effected, as well as renewals of the electric lamp, when required. The headlight casing construction shown is for illustrative purposes only and 85 not as forming any part of my invention.

The improved lamp-support and shield forming the subject of my invention comprises a vertical or substantially vertical plate portion 10, preferably with an arcuate 90 contour 10^a, to fit, or substantially fit, the curved contour of the main reflector or casing, whatever it may be, and a lower edge 10^b, preferably disposed in a horizontal plane. The plate 10 is provided with a 95 series of small inturned projecting portions, comprising side wings 11, and an upper member 12, whereby it may be attached to the casing 1, or the reflector 2, any suitable form of fastening means, a rivet, staple, or the like, as indicated at 13, being passed through the projection 12 and the casing and/or the reflector, while the side wings 11 may be notched at 11^a to drop over projections 14, carried by the sides of the casing 1. 100

Carried by the lower edge of the shield intermediate of the end wings and preferably centrally disposed with respect to the same, in the form of structure shown in Figs. 1, 2 and 3, is a bent-up portion 15, 110 which may be integral with the portion 10, and project upwardly and rearwardly of the

same. This bent-up portion 15, may be provided with any ordinary form of lamp socket 16, suitably secured thereto, said socket being adapted to receive an electric lamp 17, serving as the source of illumination. Additionally, the surface of the bent-up portion may serve as a reflector to direct the rays of light from the electric lamp toward the main reflector 2, and such surface may be 10 in a single plane, as shown in Fig. 4, or it may be concave, or a portion thereof concave, substantially as shown in Figs. 1, 2, et seq.

This bent-up portion 15 is adjustable as 15 to its angle, so that the light reflected thereby onto the surface of the main reflector 2 may be at the proper angle to insure the desired projection of the illumination through the unobstructed lower portion of 20 the front glass or lens 4 of the lamp structure. If desired, or it is necessary to insure support for this bent-up portion 15, a strap (or straps) 18 may extend between same and the shield. While this feature is shown in 25 connection with the form of structure illustrated in Fig. 4, it will be understood that it is also applicable to the structure shown in Figs. 1, 2 and 3.

In the structure illustrated in Figs. 1, 2, 30 3 and 4, I have shown the lamp-carrying portion 15, as projecting upwardly from the lower edge of the shield 10. It is obvious, of course, that this arrangement could be reversed, and in Fig. 5, I have shown a 35 shield structure having a lamp-carrying portion depending from the upper edge of the plate portion 10. Centrally or substantially centrally disposed with respect to the upper curved edge of the shield plate is a rearwardly extending portion 12^a, which may be secured to the lamp casing or the reflector by a fastening 13^a, for which purpose a portion of its wall may be struck-up, as indicated in the drawing. The portion 12^a may 40 be integral with the shield 10, and may follow the contour of the reflector 2, or casing 1, and be directly secured thereto, instead of striking up the portion illustrated in Fig. 45 5. This portion 12^a is bent to form a depending part 12^b, disposed at a suitable angle with respect to the shield, in substantially the same manner as the portion 15, illustrated in Figs. 1, 2, et seq., and which may also constitute a reflector. The surface of 50 the depending part 12^b may be in a single plane, or it may be slightly concave, so as to collect the rays of light emanating from a lamp 17^a, forming the source of illumination, and mounted in a socket 16^a, carried by the portion 12^b. If it is necessary to hold the part 12^b against vibration, it may extend to 60 and be connected to the shield, or a securing strap 18^a may be employed.

It will be observed that the source of illumination is disposed wholly above the

lower edge of the shield plate, and that the angle of the reflecting element 15, or 12^b, may be such as to properly direct the rays of light toward the surface of the reflector 2, and insure the proper reflection through 70 the lens or front glass 4 of the headlight. The rear of the casing 1 may carry a suitable insulating sleeve 20 for the passage of the current conducting cord 21, and this cord may lie on the inside of the casing or 75 between the casing and reflector, and pass to the socket carried by the supporting portion 15, or 12^b, for the electric lamp, around the edge of the shield.

The shield is made of relatively heavy 80 sheet metal, which metal may have a highly polished surface, giving a pleasing aspect at the front of the lamp, and also furnishing the desired reflecting surface.

While I have shown and described the 85 combination shield and lamp support as being carried by the reflector or the casing, it is obvious that it may be attached to the door frame, if the latter is arranged to swing on hinges, with provision for sufficient slack 90 in the current conducting cord to insure proper operation of the same.

As may be understood from the foregoing description, the combined shield and lamp support may be detachably secured to any 95 headlight structure by properly fastening the inturned portions or side wings of the plate 10 to the lamp casing, or the reflector. For lamps as now constructed, with parabolic or semi-circular reflectors adapted to 100 receive an electric lamp in the centre, the aperture for the lamp socket may receive an insulating sleeve 20, to serve as the channel for the passage of the current conducting cord to a lamp carried by my improved support and shield. With the type of lamp structure just referred to, any ordinary reflector, of semi-circular or other shape, may 105 be employed in the headlight casing; being secured therein in any suitable manner independently of the shield and the lamp support.

While I have described my improved shield and light-support as made of sheet metal, it will be obvious that other materials 115 can be employed so long as the light-support is carried by the shield in proper angular relation and provided with a reflecting surface, and the shield is arranged for detachable connection with the headlight casing.

I claim:

1. In combination with a headlight casing, the usual concave reflector, and glass closure, a light projecting and shielding device comprising a substantially semi-circular plate having integral wings thereon for attachment to the headlight casing, an angularly disposed lamp supporting member in the rear of and integral with said plate; said lamp supporting portion having a light re- 125 130

flecting surface, and a light source mounted in said light reflecting surface and facing rearwardly thereof.

2. In combination with a headlight casing, 5 the usual concave reflector, and glass closure, a light projecting and shielding device comprising a substantially semi-circular plate having integral wings thereon for attachment to the headlight casing, an angularly 10 disposed lamp supporting member in the rear of and integral with said plate; said lamp supporting portion having a substantially concave surface acting as a light reflecting surface, and a light source mounted 15 in said concave surface and facing rearwardly thereof.

3. In combination with a head light casing, the usual concave reflector, and glass closure, a light projecting and shielding device comprising a substantially semi-circular 20 plate having integral wings thereon for attachment to the headlight casing, an angularly disposed lamp supporting member in the rear of and integral with said plate and projecting upwardly from the lower edge 25 thereof; said lamp supporting portion having a light reflecting surface, and a light source mounted in said light reflecting surface and facing rearwardly thereof.

In witness whereof I have signed this 30 specification.

WILLIAM H. RAPP.
